ASH TRAY AND THE LIKE

Clarence M. Mersbach, Chicago, Ill.

Application May 24, 1933, Serial No. 672,636

3 Claims. (Cl. 131—51)

This invention relates to ash trays and the like, and among other objects aims to provide a cheap but decorative article of this character which may, if desired, be discarded after use.

5 The nature of the invention may be readily understood by reference to an illustrative construction embodying the invention and shown in the accompanying drawing.

In said drawing:

10 Fig. 1 is a plan view of an ash tray;
Fig. 2 is an elevation taken from the plane 2—2 of Fig. 1 to show the interlocking arrangement at the corner;

15 Fig. 3 is a plan view of the blank from which the tray of Fig. 1 is formed;

Fig. 4 is a tray similar to Fig. 1 in which the corner tab is provided with an elongated surface to provide a rest for a lighted cigarette or the like; and

20 Fig. 5 is a plan view of the portion of the blank from which the tray of Fig. 4 is made.

The illustrative ash tray, while made of materials and in such a manner as to reduce its cost and make it practicable to discard after use, is nevertheless appropriately decorative to encourage its use in all surroundings. Cheapness is attained by making the same from heavy paper or cardboard which is adapted to receive printed matter and appropriate decoration. As here shown, the tray 10 is stamped from a flat blank 11 of the aforesaid cardboard or heavy paper which may advantageously be surfaced with a coating of fire resisting printing ink or the like to prevent objectionable scorching or char-ring by the lighted end of a cigarette or cigar. While in most instances the ordinary heavy paper or cardboard would require no protecting sur-facing of this character, it may be advantageously added to overcome prejudice and as a further 35 assurance of safety in use. The ordinary decorative coating which may comprise any desired color including metallic finishes, may itself be designed to provide appropriate fire resistance.

The blank is preferably of triangular shape 45 and of a size which may be conveniently carried in the pocket. For example, the blank may be slightly more than five inches long on a side without being objectionably large for carrying in the pocket or placing in a flat form in a tin of 50 cigarettes. The blank is preferably scored or otherwise treated along the lines 12 to provide upwardly bendable margins 13 (in this case about three-quarters of an inch wide) which form inclined sides of the tray. In this connection it 55 should be noted that the blank is slotted along

the lines 14 between adjacent margins to permit the same to be bent up independently. The adjacent ends of the margins are provided respectively with interengageable slots 15 and tabs 16 which when interengaged serve to hold the 5 margins in upwardly bent position to provide a tray bottom 17 which is surrounded by continuous inclined sides 18.

To effect the aforesaid interengagement the tabs are preferably bent over along the lines 19 10 (which may be scored on the under face of the tabs) and inserted through the respective slots 15. If desired to provide greater permanency, the tabs may be provided with a bendable interlocking portion 20 which after it has been passed 15 through a slot may be bent down as at 21 (see Fig. 2) to prevent withdrawal of the tab from the slot. The longitudinal position of the slots 15 determines to some extent the degree of inclination of the sides.

20 The material from which the trays are made is adapted to receive printed matter such as advertising either on the bottom as indicated at 22 or along the side margins as indicated at 23, or on both. Obviously the attention value of the 25 tray as an advertising medium, is substantial. The character of the advertising may of course greatly vary. If one or more trays in blank form be furnished with a tin of cigarettes, they may desirably carry advertising relating to that brand 30 of cigarettes. While the trays in blank form may be distributed without cost if they carry advertising, the cost of appropriately decorated trays without advertising is so small as to make it possible to buy them in quantity and to discard trays after use, making it possible to abolish the distasteful task of emptying and cleaning the trays. The cheapness of the trays thus makes it possible always to have an adequate supply on hand, and minimizes the trouble and possible 35 damage usually connected with tobacco ashes.

Instead of advertising (or if desired in combination with advertising), trays may be obtained with decorative matter symbolic of a particular occasion (for example, as indicated at 24, Fig. 4) 45 without substantial cost. For example, the trays may be appropriately used as place cards at dinner parties and the like, thus serving a double function.

While the upper surface 25 of the downwardly 50 folded tab provides some support for a lighted cigarette or the like, a longer supporting surface may be provided if the tab be elongated as at 26 (see Figs. 4 and 5). The tab when folded down and interlocked with its slot presents a sub- 55

stantial supporting surface. If desired the tab may be slightly creased or scored along the line 21 to provide a groove or channel 28 extending longitudinally of the tab to hold the cigarette 5 from rolling off its support. The tab may also be provided with a bendable portion 29 which may be bent down after it has been passed through the slot to interlock the interengaged parts. The slot 30 is here shown elevated to the level of the opposite side of the tab by being formed in a projecting portion 31 along the margin 32. Thus the tab will lie level when it is folded in place and passed through the slot.

Obviously the invention is not limited to the 15 details of the illustrative construction since these may be variously modified. Moreover, it is not indispensable that all features of the invention be used conjointly since various features may be used to advantage in different combinations and 20 sub-combinations.

Having described my invention, I claim:

1. As an article of manufacture, an ash tray formed from a generally triangular blank of cardboard or the like, said blank being scored near 25 its edges to provide margins adapted to be bent up along the scored lines to provide sides for the tray, said margins being provided with interengaging slots and tabs for holding the margins in

upwardly bent condition, said tabs providing a supporting rest for lighted cigarettes or the like.

2. As an article of manufacture, an ash tray formed from a generally triangular blank of cardboard or the like, said blank having margins adapted to be bent up along the scored lines to provide sides for the tray, said blank being slitted at the corners to allow independent upward bending of said margins, said margins adjacent their ends having interengageable slots 10 and tabs adapted to be interengaged to hold said margins in inclined positions, said slots being located to position said margins in inclined position.

3. As an article of manufacture, an ash tray 15 formed from a generally triangular blank of thick paper or the like, said blank being of a character to receive printed matter on its upper face and having upwardly bendable margins for forming the sides of a tray, the adjacent ends 20 of said margins being respectively formed with a slot and a tab adapted to be interengaged to hold the margins in upwardly bent position, said tabs being elongated to present a supporting surface across the corner between said margins to provide a rest for holding a cigarette or the like out 25 of contact with the bottom of the tray.

CLARENCE M. MERSBACH.
